Edgar Nichols.

UNITED STATES PATENT OFFICE.

CARL ILIGAN, OF EAST ELMHURST, AND RALPH HESSEL, OF HOLLIS, NEW YORK.

BUTTON.

1,367,547.

Specification of Letters Patent.

Patented Feb. 8, 1921.

Application filed June 9, 1920. Serial No. 387,536.

To all whom it may concern:

Be it known that we, CARL ILIGAN and RALPH HESSEL, residing at East Elmhurst, Long Island, in the county of Queens and State of New York, and Hollis, Long Island, in the county of Queens and State of New York, have invented certain new and useful Improvements in Buttons, of which the following is a specification, such as will enable those skilled in the art to which it appertains to make and use the same.

This invention relates to buttons for use in connection with garments of various kinds and classes, such as coats, vests, trousers and the like; and the object thereof is to provide an improved button of this class which may be quickly and easily secured to a garment of any kind or class without the use of a needle and thread; and with this and other objects in view the invention consists in a button of the class specified, constructed as hereinafter described and claimed.

The invention is fully disclosed in the following specification, including the accompanying drawing, in which the separate parts of our improvement are designated by suitable reference characters in each of the views, and in which:—

Figure 1 is a view showing our improved button in use;

Fig. 2 a back face view of the button;

Fig. 3 a view similar to Fig. 2 but showing a modified form of the button; and,

Fig. 4 a section on the line 4—4 of Fig. 3.

In the practice of our invention, we provide a garment button *a* comprising a main button member *a*² provided at its back with a central shank *a*³, the free end of which is provided at one side with a main projecting pointed prong *a*⁴ and at the opposite side and in the same plane as the prong *a*⁴ with a supplemental prong *a*⁵ which is shorter than the prong *a*⁴.

The prongs *a*⁴ and *a*⁵ are both curved inwardly slightly or made hook-shaped in form, and the prong *a*⁵ is preferably about half the length of the prong *a*⁴, or a little over half the length. The button, as shown in Figs. 1 and 2, may be made in any desired manner and of any preferred material, but in Figs. 3 and 4 is shown a button *b* stamped from sheet metal and comprising a main button member *b*², having a shank *b*³ provided

with prongs *b*⁴ and *b*⁵, said shank and prongs being cut from the main part of the button as shown at *b*⁶ and bent into the desired position.

In Fig. 1 of the drawing, we have shown at *c* a piece of cloth and in applying the button or securing it to the cloth, the cloth is firmly held and the prong *a*⁴ and shank *a*³ of the button are passed through the cloth and moved or pressed in the direction of the arrow *x*. This operation elongates the hole 65 in the cloth *c*² through which the shank *a*³ and the prong *a*⁴ were passed, and when this is done the button is pressed against the cloth and turned in the direction of the arrow *x*², and in this operation the shorter 70 prong *a*⁵ passes through said elongated hole, and when the pressure on the button is released the hole in the cloth closes up and the button is held as shown in Fig. 1.

It will be understood that the views of the accompanying drawing are enlarged and the proportions of the parts of the button, in practice, are such that the prongs *a*⁴ and *a*⁵ will fit against the back of the goods and the button cannot be removed from the cloth or goods without tearing said cloth, or breaking the button, and in this way we provide a button which may be used in connection with garments of both men and women, and which may be easily secured in position 85 without the use of a needle and thread, and which may be used whenever devices of this class are required.

It will also be understood that our invention is not limited to the comparative lengths 90 of the prongs *a*⁴ and *a*⁵, nor to the comparative lengths of said prongs and that of the shanks *a*³, nor to the material or size of the button, and changes in and modifications of the construction herein described may be 95 made, within the scope of the appended claims, without departing from the spirit of the invention or sacrificing its advantages.

Having fully described our invention, what we claim as new and desire to secure 100 by Letters Patent, is:—

1. A button of the class described having a shank provided at its end with an integral arc-shaped cross head and the ends of said cross head being pointed to form prongs.

2. A button of the class described having a shank provided at its end with an integral arc-shaped cross head and the ends of said

cross head being pointed to form prongs, and one of said prongs being longer than the other.

3. A button of the class described composed of a single piece of metal fashioned to form a shank at one end of which is a disk-shaped head member and at the other end of which is a cross head member, and the ends of said cross head member being pointed to 10 form prongs.

In testimony that we claim the foregoing as our invention we have signed our names in presence of the subscribing witnesses this 7th day of June 1920.

CARL ILIGAN.
RALPH HESSEL.
